ADJUSTABLE BODY SUPPORT FOR CASKETS

Cyril B. Quaka, Bridgeport, Conn.

Application April 28, 1949, Serial No. 90,117

5 Claims. (Cl. 27—12)

1

This invention relates to an adjustable body support for caskets, and has for an object to provide a device to facilitate the proper positioning of the body or corpse in a casket.

Another object is to provide an adjustable body support to be used in caskets and to provide with this a simple adjustable and easily manipulated device for the convenience of the funeral director to facilitate the proper positioning of a body in the casket in an easy, quick and efficient manner.

A further object is to permit better positioning of the body, resulting in a better pose of the body, thereby enhancing the appearance of the layout.

A still further object is to produce a more dignified arrangement of the body, since it is customary to display bodies in a very high position in order to bring about a better looking display, and because of this it therefore becomes necessary to lower the body sufficiently to clear the casket lid when closed. With this device this lowering operation may be accomplished quickly and with dignity.

A particular object is to provide an improved adjustable lifting device for the supporting frame of the support which will be of rigid construction with both sides so tied together that it eliminates all possibility of unequal support to either side of the bed, thus eliminating any tipping or dropping of either side and yield or undesirable flexibility in the device, especially when supporting a body load.

Another object is to provide a more proper support for the shoulder portions of the body to give a better pose, and still another object is to provide an adjustable mechanism which will permit easy and quick adjustment of the height of the body in the casket, with a minimum of effort on the part of the funeral director.

With the foregoing and other objects in view, I have devised the construction illustrated in the accompanying drawings forming a part of this invention. It is, however, to be understood the invention is not limited to the specific details of construction and arrangement shown, but may embody various changes and modifications within the scope of the invention.

In these drawings:

Fig. 1 is a top plan view of the device showing it located in the box structure of a casket;

Fig. 2 is a partial side elevation and partial

2

section, the section at the front of the support being substantially on the line 5—5 of Fig. 1 and with the intermediate portion substantially on the line 2—2 of Fig. 1;

5 Fig. 3 is a transverse section substantially on line 3—3 of Fig. 1;

Fig. 4 is a transverse section substantially on line 4—4 of Fig. 1;

Fig. 5 is a longitudinal section substantially on line 5—5 of Fig. 1;

Fig. 6 is a top plan view of a portion of the adjusting means at an intermediate portion of the support with parts broken away to more clearly show the construction;

15 Fig. 7 is a detail section substantially on line 7—7 of Figs. 2 and 6, and

Fig. 8 is a side view looking toward the bottom of Fig. 6.

The device comprises a frame 10 of any suitable construction. The particular construction shown comprises longitudinal side members 11 and cross members 12 and 13 at the opposite ends thereof, with any suitable or desired number of intermediate cross members 14, 15 and 16. Also the side

25 members may be connected by any suitable number of flat crossed bracing bars or strips 17. Cross members 12 and 14 are also connected by intermediate longitudinal bars 18 and 19. The side bars 11 and the cross bars 12, 13, 14, 15 and 16 are preferably of angle shape in cross-section, although they may be formed of other shapes if desired. The angle shape, however, gives great strength and rigidity for the amount of material in the bar and therefore gives good strength and rigidity with less weight. The members may be connected by any suitable means, such, for example, as welding or riveting as found desirable.

35 This frame structure, however, may be varied as found desirable and it may be made of different material. It is preferred to make it of aluminum as this produces a light weight structure of required strength, but any other suitable materials may be used, such, for example, as wood, other metals, or other suitable materials. It

45 is also not necessary to use an open frame construction, as practically any shape of structure for support for the body may be used, as, for example, merely a flat board construction of proper length and width, and in the specification 50 and claims the word "frame" is used in a general

broad sense to include any of these constructions.

A particular and unique construction of the device is the supporting means for the frame or body support. There are preferably provided two of these adjustable supporting means for the frame, one being located adjacent the head end of the frame at about the location of the shoulders of the body and indicated as a whole at 20, and the other is located at about the hips or the lower end of the trunk of the body and indicated as a whole at 21. These two devices are practically the same in construction and arrangement and operate in substantially the same way, but the lower one 21 is changed slightly in respect to the arrangement of the release mechanism to make it more accessible for manipulation at the side of the frame, which is wider than the head portion and therefore there is less clearance between the sides of the frame and the sides of the casket at this portion than at the head portion. This is shown in Fig. 1, in which the forward end portions 11a of the side members 11 are bent inwardly toward each other somewhat at the points where the cross member 14 is connected to the side members, and the head end bar 12 is shorter than the bar 14 at the opposite end of the frame. Bending these bars inwardly also bends the side members 11 in the vertical plane because of their angle shaped cross section, so that the end bar 12 is somewhat lower than the bar 14 with the end portions 11a of the bars 11 inclining downwardly from the bar 14 to the bar 12, as shown in Fig. 2. To give a better support to the shoulders of the body there is also provided an upwardly transversely curved auxiliary supporting bar 22 directly over or adjacent the bar 14, this bar being secured at its opposite ends either to the side members 11 or to the bar 14 adjacent these side members as indicated at 23, and curved upwardly so as to be convex between these points as shown in Fig. 3.

The adjustable supporting structure 20 for the frame comprises a transverse base bar 24 resting on the bottom 25 of the casket 26 and secured to the bottom of the casket to form a support for the frame. It may be secured to the bottom of the casket by any suitable means, such, for example, as nails or screws 27 when the casket is of wood, or it may have clamps 28 at its opposite ends to be clamped against the upright sides 26a of the casket when it is made of metal, or of course these clamps could also be used in the case of a wooden casket, if desired. This clamp may be of any suitable construction, but in the arrangement shown comprises a cup or flat washer 29 on an adjusting screw 30 threaded into the upright bent end 31 of the base bar 24. These screws may be operated to clamp the cups or washers 29 against the sides of the casket by any suitable means, as for example, the looped ends 32 or other suitable means.

Pivoted to base bar 24 are supporting legs 33 preferably being pivoted at 33a to angle lugs 34 mounted on the bar 24. These legs are formed of a substantially U-shaped structure, as shown in Figs. 3 and 4, including the spaced upright side legs 33 and connecting bar 35. This can be bent to this shape from a bar of suitable width and thickness, and as this provides a unitary one-piece structure it makes a very rigid construction and insures that both legs 33 move together in the adjusting or lifting operation.

It also insures that one side will not sag when the weight of the body is placed on the frame. These legs are further strengthened and stiffened by similar arms 36, also preferably bent up

from a bar to a substantially U shape with a connecting cross bar 36a and pivoted at any intermediate point 37 to the legs 33 and at their upper ends are pivoted to the bars 18 at 38. Also 5 pivoted to the frame members 18 at 38 is a pair of ratchet bars 39 provided on their lower edges with a series of ratchet teeth 40 with notches between them adapted to receive a cross rod 41 connecting the free upper ends of the legs 33. 10 These ratchet bars 39 are connected at their free ends by a transverse manually operable release bar 42. The connecting rod 41 projects beyond the legs 33 and slides at each of its opposite ends on a suitable guide and support 43 mounted on the insides of the members 18. These are angle bars with their horizontal flanges at the lower edge and they are located so that there is a clearance space between this flange and the top flange of the members 18 to 15 permit movement of the rod 41 and also provide clearance for release of the ratchet members 39 by lifting them. The weight of the frame is carried by the top or horizontal flanges of bars 18 resting on the upper ends of legs 33. The 20 operating of raising the head end of the frame may be assisted by a relatively heavy spring 44 connected at one end to the rod 41 and at its opposite end to some part of the frame 10; such, for example, as the upright flange 45 of the cross bar 14.

In lowering the head portion of the frame to bring the upper portion of the body to the proper level, the director merely passes his fingers under the side bars 11 and lifts the cross or release bar 35 42. This will raise the ratchet bars 39, releasing the rod 41 from the notches in the ratchet in which it may be located, and thus releasing this rod to permit it to slide longitudinally in its guideways to vary the angle of the legs 33 and thus the height of the frame, as indicated by the full and dotted lines in Fig. 5. The operation of raising the frame and body and thus reducing the strain of lifting required by the operator, is assisted by the spring 44 which tends to shift the legs 33 to the upright position. The 45 teeth 40 of the ratchet and therefore the notches between them are inclined backwardly and downwardly so as to be sure the weight of the body will not force the rod out of these notches to permit the frame to drop. As the base bar 24 is secured to the casket it is held against being lifted upon lifting of the frame 10 and thus insures that the legs 33 will be swung or raised to the proper position on lifting of the frame. Also because of the incline to these notches it is not necessary to lift the bars 39 to release rod 41 in raising the frame. All that is necessary is merely to lift up on the frame.

The second lifting and supporting device 21 is substantially the same as that of 20 except that 60 it is made somewhat wider because it is located at a wider part of the frame 10, and the release ratchet is slightly different. It comprises a base bar 24 the same as that of the first form, which is secured to the bottom of the casket and has the angle lugs 34 mounted on its upper surface to which are pivoted the supporting legs 46. These are the same construction as legs 33 being formed by bending a bar to substantially U shape and connected by the cross bar 47. They are pivoted to the lugs 34 at 48 and they are strengthened by the arms 49 also formed as a substantially U-shaped structure with a connecting bar 50 and pivoted to each leg 46 at an intermediate point 51. At their upper ends they are pivoted to side

frame members 11 at 52 and the free ends of the legs 46 are connected by the transverse rod 53, the opposite ends of which extend beyond these legs and are guided for longitudinal movement in the frame by the angle guides and supports 54 corresponding to the angle guides 43 for the rod 41. This rod is held in the adjusted position to thus retain the legs 46 at different angular positions or different heights for the frame by ratchet bars 55. These are flat bars provided with a series of teeth and notches 55' in their lower edges to receive the rod 53 and hold it in different adjusted positions, and they are mounted on the side bars 11 of the frame by means of suitable hinges 56. In the normal position they are in a 15 depending or upright position as shown in Fig. 7, but they may be released by swinging their lower edges inwardly to a substantially horizontal position, as indicated by the dotted lines in Fig. 7, to thus remove them from the rod 53 and release this rod to permit the rod to slide longitudinally in the frame and permit raising or lowering of the frame to different heights. These ratchet bars may be swung to this position by the operator inserting his fingers under the side members 11 at the outer edges of the frame, and then he may lift the frame or lower it as desired. After adjusting the frame to the proper height, release of these ratchet bars will permit them to drop or swing to the upright position and lock the rod 53 and the supporting legs 46 in their adjusted positions.

It is to be particularly pointed out that the U-shaped legs and arms 33, 36 and 46, 49 for supporting the frame due to this construction give 35 rigidity and a support which will not collapse by weight on one side of the frame. This gives rigidity and proper support at all times and insures that both sides or both feet must move or act together so that in adjusting the frame by raising or lowering, one side cannot lag behind or tip relative to the other. The device is used with a mattress placed on top of the frame when the device is in a casket. There is also a pillow used for the head on top of the head end of the mattress. As it is customary to display bodies in caskets in a very high position in order to bring about a better looking display, this device permits the director to raise the body quickly and easily to the proper level. However, because of this high position it is necessary to lower the body to clear the cover in closing the casket. This device permits this lowering to be accomplished quickly and with dignity, as all the director has to do is insert his fingers under the sides of the frame and release the ratchets to permit lowering of the body. The curved transverse supporting bar 22 gives a better positioning of the shoulder portion of the body and a better support for the shoulders. This brings about a better posture and appearance. The device permits the director to raise the body to any desired height quickly and with very little effort, the effort being still further reduced by the springs 44 and 51.

Having thus set forth the nature of my invention, I claim:

1. An adjustable body support for caskets comprising a frame to support the body in the casket, an adjustable supporting means for the frame comprising a base bar, means for securing said bar in the casket, laterally spaced supporting legs pivoted at their lower ends to the bar, a transverse rod connecting the upper ends of the legs, guides on the frame for the ends of the rod permitting longitudinal sliding movement of the rod

5 in adjusting the height of the frame, a toothed rack hinged at each side of the frame and engaging the rod to retain it in different longitudinal positions, and said racks being accessible at the side of the frame and swingable laterally inward to release them from the rod to permit adjustment of the height of the frame.

2. An adjustable body support for caskets comprising a frame to support the body in the casket including laterally spaced longitudinally extending side members, cross members connecting the side members including cross members at the opposite ends of the side members and intermediate cross members, a cross member extending between the side members at a position to form a support for the shoulder portions of the body and curved upwardly between the side members, and an independently adjustable support for each end of the frame to retain it at different heights in the casket.

3. An adjustable body support for caskets comprising a horizontal frame to support the body in the casket, an independent adjustable supporting means for each end of the frame, each supporting means comprising a transverse base separate from and independent of the other supporting means, independent means for securing the base of each supporting means on the bottom of the casket, each supporting means including a pair of laterally spaced supporting legs pivoted to its base at their lower ends and slidably connected with the frame at their upper ends to vary the inclination of the legs and the height of the adjacent end of the frame above the base, a transverse member rigidly connecting the legs of each supporting means so they must move together at all times, and an independent releasable catch for each supporting means for holding the legs of this means in different inclined positions to independently adjustst the height of each end of the frame.

4. An adjustable body support for caskets comprising a horizontal frame to support the body in the casket, an independent adjustable supporting means for each end of the frame, each supporting means comprising a separate transverse base bar, independent means for securing each base bar in the casket, each supporting means including a pair of transversely spaced supporting legs pivoted at their lower ends to the corresponding base bar, means securing the upper ends of the legs to the frame to slide longitudinally of said frame, a transverse member rigidly connecting the legs of each pair so they must move together, a link for each leg pivoted at one end to the frame and at its other end to an intermediate point of said leg, a transverse member rigidly connecting the links of each pair of legs so they must move together, an independent releasable catch 60 means on the frame for each supporting means for holding the slidale ends of the legs of that supporting means in different positions to support the adjacent end of the frame at different heights, and separate manual means accessible at a side of the frame to independently release the catch means for each supporting means.

5. An adjustable body support for caskets comprising a horizontal frame to support the body in the casket, an independent adjustable supporting means for each end of the frame, each supporting means comprising a transverse base bar, means for securing each base bar in the casket, each supporting means including a substantially U-shaped integral structure including spaced side legs and an intermediate connecting bar, means

7
pivotally connecting the lower end of said structure to the corresponding base bar, a transverse rod connecting the upper ends of the legs of each structure, guides on the frame for the ends of each rod permitting longitudinal sliding movement of the rod in adjusting the height of the adjacent end of the frame, a separate pivoted toothed rack engaging each rod to retain it in different positions, and each rack being independently accessible at a side of the frame for manually shifting the rack to release the rod held thereby and permit independent adjustment of each supporting means to independently adjust the height of each end of the frame.
